UNITED STATES PATENT OFFICE.

HOVNER GREENSPOON, OF LOS ANGELES, CALIFORNIA.

WINDOW AWNING.

Application filed September 15, 1926. Serial No. 135,690.

My invention is a window awning formed of a structure which may be readily detached from a building or the like where it is installed and may be readily detached from the framing supporting and stretching the awning.

An object of my invention is to form an awning of canvas or the like having a series of hooks and eyes connecting same to a building structure. The awning is provided with a hinged or folding frame to hinge up against the building, the awning being connected to same by a series of hooks and eyes.

My invention is illustrated in the following drawings, in which:

Figure 1 is a perspective view of an awning constructed in accordance with my invention;

Fig. 2 is a vertical transverse section on the line 2—2 of Fig. 1, in the direction of the arrows;

Fig. 3 is a vertical sectional view of the connection from the awning to the frame;

Fig. 4 is a transverse sectional detail view showing the connection of the awning to the building structure;

Fig. 5 is a plan view of the frame leaving out the ropes and pulleys for hinging same upwardly.

Fig. 6 is a section in elevation, showing the manner of attaching the upper portion of the awning to the building structure and the attachment of the pulleys for the operating cords to the fabric of the awning;

Fig. 7 is an inside view of Fig. 6.

In regard to my invention, the wall of a building is designated by the numeral 1, having a window or other opening 2 therein. An awning frame designated by the numeral 3 comprises a pair of base members 4 to be secured to the wall of a building, the arms 5 connected to the bases by a pivot pin 6 having a cross rail 7 connecting the bars at their outer ends. The arms and the bars are preferably formed of an integral tubing.

The awning has a roof structure 8, end walls 9 and an apron 10 over the bar 7. The manner of fastening the awning to the building and the frame is substantially as follows:

A series of eyes 11 are secured to the building at the proper height and a series of snap hooks 12 secured to the roof part of the awning are connected to the eyes. A series of eyes 13 are attached to the bar 7 and a series of similar snap hooks 14 are connected thereto, thus firmly attaching the awning to the

building and to the cross bar and allowing same to be detached. If desired a certain number of snap hooks and eyes designated by the numeral 15 may be used to connect the end walls 9 of the awning to the arms 5. If desired hooks and eyes 16 may connect the end walls 9 of the awning to the building structure.

The manner of raising and lowering the awning is substantially as follows:

Flexible side cables 17 are connected to the bar 7 of the frame. These pass through pulleys 18 and 19, one of the cables also passing through an additional pulley 20 having the downward leads 21 which may be manually operated to raise and lower the awning frame and thus the awning.

From the above description in connection with the drawings, it is believed apparent how my awning will be attached and readily detached from the building, the snap hooks and eyes allowing this feature to be readily accomplished.

In attaching the awning to the building structure or to the frame I utilize what are known in the trade as harness snaps, these having a hook portion with a spring, the spring engaging the end of the hook and securing the eye when caught in the snap from becoming unfastened.

It is to be noted that the pulleys 18, 19 and 20 are supported from the fabric of the awning, the preferable way to do this is to secure a snap hook indicated by the numeral 22 to each corner of the awning, these hooks being preferably of the harness snap type and engaging the eyes on the building structure, the pulleys being fastened to the ring 23 of the harness snap hooks. If desired the ring part of the snap hook may have a rivet 24 therethrough securing same to the top of the awning.

The free ends of the ropes or cables may be secured to any suitable part of the building. Thus when raising and lowering the awning the cables run through the pulleys attached to the harness snaps of the awning and if it is desired to detach the awning from the building it is merely necessary to undo the snap hooks and the frame and this single operation removes the pulleys and the operating cables from the building structure.

It is to be noted that the cables 17 are connected at their lower ends to the snap hooks 24, which hooks are connected to the eyes 13 on the frame

bar 7 and that the snaps are secured to the fabric. By this construction the cables are secured to the snap hooks at the lower part of the awning roof, such hooks being fastened to the frame bar and at the upper edge of the roof part of the awning the cables are roved through the pulleys, these pulleys being secured to snap hooks which in turn are fastened to the fabric of the awning and 10 such hooks being caught into the eyes. Therefore when the ropes or cables are pulled on to raise the awning there is no stress brought on the fabric of the awning tending to tear same and by this construction 15 it will be seen that by unsnapping the snap hooks from the eyes attached to the building and to the eyes attached to the frame bar, that the whole awning may be removed with the cables and pulleys for 20 operating same.

From the above description it will be apparent that my type of awning is suitable for circumstances in which it is desired to readily attach and detach the awning from 25 the building and from the frame and, if desired, to detach the frame from the building. On account of the upper snap hooks 12 being secured to the underneath part of the roof structure of the awning, a person may 30 reach out of a window and hook the snap hooks in the eyes 11 which may, if desired, also be inserted in the window frame by reaching out of a window. The frame 3 may also be readily attached to the base members 4 by reaching out of the window and 35 inserting the pivot pins. On account of the snap hooks 14 being on the inside of the awning at the lower portion, these may be readily snapped into the eyes 13 on the bar 40 of the frame, the apron part hanging down over such frame. It will thus be seen that my awning and the frame is readily attached to the building by reaching out through a window and it is not necessary to employ 45 awning workers to install and to take down the awning. This is a material feature of the advantage of my awning, especially in climates where they have to be put up in the 50 spring of the year and taken down in the autumn.

Another advantage of my awning is on account of connecting the cables 17 to the hooks at the lower part of the roof structure and passing such cables through pulleys 55 which are attached to the hooks at the upper part of the roof structure and thus when the cables are secured to a cleat or the like there is no necessity of material strain being brought on the roof structure itself and thus 60 the canvas forming the awning is not required to support the weight of the frame nor the various stresses due to wind, etc.

Although my invention is of a simple

character, it may be changed in general construction or in specific details to adapt same 65 to different installations. Such changes would be within the spirit of my invention as set forth in the description, drawings and claims.

Having described my invention, what I 70 claim is:

1. A window awning having a fabric roof structure, a first set of fastening devices secured to the upper edge and the underside of said roof structure, means to secure said fastening devices to a building above a window, a second set of fastening devices 75 secured to the lower part of the roof structure on the underside, a frame connected to the building, and means to attach the second 80 fastening devices to the frame.

2. A window awning comprising in combination an awning having a fabric roof structure, a first set of fastening devices secured to the upper portion and underside of 85 said roof structure, pulleys connected to some of said fastening devices, means to connect said fastening devices to a building above a window, a second set of fastening devices secured to the lower part of the roof 90 structure on the underside, a frame secured to the building, means to secure said second fastening devices to the frame, cables secured to some of said second fastening devices and passing underneath the roof structure 95 and through the said pulleys.

3. A window awning comprising in combination a building structure having a series of eyes over a window, an awning having a fabric roof structure, snap hooks secured to the roof structure at the upper part and on the underside thereof, said snap hooks engaging the said eyes, a frame connected to the building, a second series of snap hooks connected to the roof structure at a lower 100 portion and on the underside, there being means to connect said second series of snap hooks to the frame.

4. A window awning comprising in combination a series of eyes attached to a building over a window, an awning having a roof structure, a first set of snap hooks attached to the upper part of the roof structure on the underside, said hooks engaging the said eyes, pulleys connected to some of said hooks, 115 a second series of snap hooks attached to the roof structure at a lower part and on the underside, a frame pivotally connected to the building, means on said frame to engage the second set of hooks, and flexible cables attached to some of the second set of hooks 120 and passing through said pulleys.

In testimony whereof I have signed my name to this specification.

HOVNER GREENSPOON.
